WITNESS:

UNITED STATES PATENT OFFICE.

SIMEON ISAAC HUSSEY, OF LYONS, GEORGIA.

TRUSS.

Application filed August 31, 1922. Serial No. 585,429.

This invention comprehends improvements in trusses, and provides a construction designed to support the abdomen in addition to its use in the capacity of a truss, 5 in which capacity it is adapted to support the inguinal hernia, single or double, femoral hernia, direct or indirect. It is also advantageous for use by athletes as a support for the abdomen and adjacent parts 10 of the body when engaged in exercises to develop these portions of the body irrespective of whether a rupture exists or not.

The nature and advantages of the invention will be better understood when the 15 following detailed description is read in connection with the accompanying drawing, the invention residing in the construction, combination, and arrangement of parts as claimed.

20 In the drawing forming part of this application, like numerals of reference indicate similar parts in the several views, and wherein:—

25 Figure 1 is a front elevation of the device forming the subject matter of the invention.

30 Figure 2 is a view in elevation of the pad adapted to be arranged at the back of the user and showing the manner by which it is supported by the body straps.

Figure 3 is a sectional view through the 35 truss pad.

Referring to the drawing in detail, A indicates a two-part abdominal support or 40 truss, and these parts are indicated at 10 and 11 respectively. The parts may be used singly or doubly, and when used in conjunction are arranged in the manner illustrated in Figure 1. Each part is of 45 the proper size or proportion to cover one side of the abdomen and when the parts 10 and 11 are used together, the adjacent edges are lapped or otherwise suitably associated, and the combination of the said parts 50 unitedly define an area sufficient to extend across the abdomen to properly support the same. The parts 10 and 11 are preferably constructed from a single piece of leather, but may be constructed from any single 55 piece of material. Each part has associated therewith a body strap 12, which is adapted to embrace the waist of the user, the straps being connected by means

of suitable buckles 13. The straps support a pad 14 which is adapted to be arranged 55 at the back of the user, the pads supporting parallel strips 15 between which and the pad proper the pads are passed. It is of course obvious, that the straps can be adjusted to exert the proper degree of pressure against the abdomen as will be readily understood. The lower end of each part 60 10 and 11 supports the truss pad 16 at points where the hernia protrudes. The outer side of each part 10 and 11 supports a 65 leather disk 17 equipped with headed elements 19 to accommodate the loops 20 carried by the adjacent ends of the tapes which are arranged to surround the body of the user above and below the hips. These 70 tapes are indicated at 20 and 21 respectively, the latter being formed with a loop at one end as at 22 to receive the tape 20. The tapes 20 are connected together at the 75 back of the user by means of a buckle 23 arranged at one side of the pad 14. The tapes 20 pass between the strips 15 in the same manner as the straps 12. The tapes 20 are preferably elastic and can be adjusted to exert the proper pressure against 80 the body of the user and are also arranged to prevent upward movement or displacement of the device incident to the movements of the body.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claimed is:—

In a device of the character described, an element adapted to be arranged across the 95 abdomen, a waist encircling belt carried thereby, an elongated back embracing pad, a second waist encircling belt extending across the pad below the first mentioned belt, spaced vertically disposed strips supported on said pad and secured thereto at the ends and at points intermediate their 100 length to receive said belts and hold the latter equidistantly spaced apart in parallelism, a reinforcing element arranged 105 across the pad between said belt and termi-

nally secured to said strip and also secured to said pad at spaced points throughout its length, a truss pad carried by the inner face of said element, wear resisting disks secured to the outer face of said element, studs projecting therefrom, and limb embracing elements extending from the lower-

most belt and provided with loops adapted to engage the studs for the purpose specified.

In testimony whereof I affix my signature.

SIMEON ISAAC HUSSEY.
